DESIGN FOR A LACE FABRIC OR SIMILAR ARTICLE

Gustav Zellweger, Palisades, N. J.

Application December 17, 1937, Serial No. 73,676

Term of patent 3½ years

To all whom it may concern:

Be it known that I, Gustav Zellweger, a citizen of the United States, residing in Palisades, county of Bergen, and State of New Jersey, have invented a new, original, and ornamental Design for a Lace Fabric or Similar Article, of which the following is a specification, reference being had to the accompanying drawing forming part thereof.

The drawing is a plan view of a lace fabric or similar article showing my new design.

The design which is an open lace fabric is shown on a black surface to bring out the details thereof.

I claim:

The ornamental design for a lace fabric or similar article as shown and described.

GUSTAV ZELLWEGER,
